UNITED STATES PATENT OFFICE.

ALICE M. GAMLIN, OF NEW YORK, N. Y.

DESIGN FOR A PICTURE-FRAME OR SIMILAR ARTICLE.

SPECIFICATION forming part of Design No. 32,285, dated February 27, 1900.

Application filed January 5, 1900. Serial No. 514. Term of patent 3½ years.

To all whom it may concern:

Be it known that I, ALICE M. GAMLIN, a citizen of the United States, residing at No. 125 West Ninety-sixth street, New York, in the county of New York and State of New York, have invented and produced a new and original Design for a Picture-Frame or Similar Article, of which the following is a specification, reference being had to the accompanying drawing, forming part thereof.

As shown in the drawing, my design consists of the frame B, having an ornamental border A at the outer edge thereof and a similar ornamental border C arranged around the inner edge of the frame, as shown. Each of such ornamental borders is made in the shape

of a series of pointed tongues of flame, as shown.

The design is applicable to picture, looking-glass, or other similar frames or articles. ²⁰

Having described my invention, what I claim as new, and desire to secure by Letters Patent, is—

The design for a picture-frame or similar article, as herein shown and described. ²⁵

In testimony whereof I have hereunto set my hand in presence of two subscribing witnesses.

ALICE M. GAMLIN.
